NESTABLE CHAIR

Louis Dellert, Brooklyn, N. Y.

Application November 30, 1934, Serial No. 755,477

5 Claims. (Cl. 155—2)

This invention relates to an improved nestable chair, an object being to form a very simple and strong construction which may be readily nested with the legs resting on the floor.

5 Another object of the invention is to provide a nestable chair formed to permit a plurality of identically constructed chairs to nest from the front, the structure presenting a comparatively wide chair at the front with the front legs extending inwardly towards each other from the rear edge of the chair structure.

10 A further object, more specifically, is to provide a chair which may be nested with similar chairs wherein there is used a U-shaped frame with the front legs connected to the frame at the margin or lower edge of the frame so that the respective frames of a plurality of chairs may be slid together during the nesting action.

15 In the accompanying drawings—

20 Figure 1 is a top plan view of a chair disclosing an embodiment of the invention, the back being broken away and shown in section, and part of the seat being broken away for better illustrating the frame structure and how a plurality of chairs 25 may be nested;

Fig. 2 is a side view of the structure shown in Fig. 1, the upper part of the back of the chair being broken away and the seat member being shown somewhat raised;

30 Fig. 3 is a front view of the structure shown in Fig. 2, with a part of the back being broken away and also part of the various legs;

Fig. 4 is a fragmentary sectional view through Fig. 1 on the line 4—4;

35 Fig. 5 is an enlarged perspective view of the front of one of the side frames with its leg fitting, the same being shown in connection with part of the front leg illustrated in dot-and-dash lines; and

40 Fig. 6 is a perspective view of the upper part of one of the front legs, illustrating the slot for receiving part of the fitting shown in Fig. 5.

Referring to the accompanying drawings by numerals, 1 and 2 indicate front legs, and 3 and 4 indicate rear legs, said rear legs preferably merging into a back 3, though not necessarily. If desired, the rear legs could be cut off and the back eliminated. However, for ordinary use in homes and elsewhere, the back is very desirable and may merge into the rear legs or be connected therewith in any desired manner. The front and rear legs are connected by a frame 6, which is formed of metal, while preferably the front and rear legs are formed of wood. The frame 6 includes a U-shaped structure, as shown

in Fig. 1, having side bars or rails 7 and 8, a rear bar 9, front fittings 10 and 11, and rear fittings 12 and 13. The side bars 7 and 8 are preferably rectangular and tubular, as shown in Fig. 4. These side bars are preferably welded to the rear bar 9, which is also rectangular and preferably square in cross section, though not necessarily so. The rear bar 9 is preferably provided with an aperture 14 in front of each of the rear legs for the reception of screws 15. 10 When the respective rear bar 9 and side bars 7 and 8 are rectangular in cross section, a very rigid frame is presented, the side bars 7 and 8 flaring from the rear to the front. The fittings 12 and 13 are welded to the rear or back bar 9 15 and accommodate screws 16, which with the respective screws 15, firmly secure the rear legs 3 and 4 to the bar 9. The fittings 10 and 11 at the front are welded to the under surface of the front of the side bars 7 and 8 and provide means whereby the front legs 1 and 2 may be secured in place. 20

From Fig. 5 it will be observed that the front fittings are each provided with a flange or web 17, which fits into the slot 18 in the leg so that the screws 19 and 20 may be screwed into the leg and through the respective apertures 21 and 22 for holding the leg rigidly to the fitting. It will be understood that the top of the leg presses tightly against the top plate 23 of the fitting and 30 one of the sides of the leg fits against the depending flange 24, so that when the screws 19 and 20 are in position the leg is rigidly mounted in place. As clearly shown in Fig. 1, the respective legs are arranged so that their upper 35 ends will be in line with the lower edge of the seat frame 6 so that two or more chairs of identical construction may be nested with the frames of the respective chairs sliding over the respective plates 23 as they move to the dotted position 40 shown in Fig. 1.

A seat member 25 is provided, the same being of any desired kind and being supplied with one or more hinges 26 for connection with other parts of the chair. If desired, these hinges could 45 connect the seat structure 25 with the frame 6, but as illustrated in the drawings, these hinges connect the seat structure with the upper part of the rear legs. As far as the mounting of the seat structure is concerned, the same could be 50 pivotally connected in any desired manner, or could be held in place by any suitable means so that it would be removable when two or more chairs are to be nested. As a preferred structure, however, the seat structure 25 is piv- 55

totally mounted so as to be swung upwardly to a substantially vertical position when two or more chairs are to be nested. As illustrated in Fig. 2, this results in a notch or space 27 being provided above each of the front legs 1 and 2. In order to permit the seat structure 25 to extend forwardly to the outer edge of the front legs and, at the same time, fill the space 27, there is provided a front block 28 for each leg, said front blocks being connected in any desired manner with the seat structure 25. When the seat structure 25 is in its lowered or operative position, the appearance of the chair will be as shown in Fig. 3. In order to brace and also make more pleasing the front part of the chair, a bracing bar 29 is connected to the front edge of the seat structure on the lower surface thereof and also to the blocks 28. By this construction, whenever the seat structure 25 is swung upwardly out of the way, or moved out of the way in any other manner, the space or notch 27 will be left unoccupied and, consequently, chairs may be readily nested without the legs being moved from the floor, the common nesting being from the front. While the blocks 28 are preferably carried by the seat structure 25, it is evident that they may be mounted in other ways, as, for instance, so as to swing to one side instead of moving upwardly with the seat structure.

In forming and positioning the legs 1 and 2, they are preferably arranged as shown in Figs. 1 and 2. The finished structure will appear as shown in Fig. 3, from the front and present a chair having the desired width in the front and almost the same width in the back. In this way a desired and pleasing shape is provided for the chair and, at the same time, a very strong and rigid structure presented which may be provided with the back 5 or this back may be eliminated; also, preferably a loop member 30 is connected to the rear legs, as shown in Figs. 1 and 2, whereby a desired hat support is provided. This arrangement of hat support officially performs its duties but does not interfere with the nesting of the chairs.

I claim:

1. A nestable chair including a U-shaped frame having a rear connecting transverse member and two diverging side members, said frame being open at the front, a movably mounted seat normally resting on said frame and movable to a position away from the frame when a plurality of the chairs are being nested, a pair of front legs, a pair of rear legs, means for rigidly securing said rear legs to the rear part of said frame, and means for rigidly securing the upper ends of said front legs to the bottom of the front end of said side members, said front legs having a portion extending inwardly of said front end of said side members with the side members positioned so that the side members of one chair may fit within the side members of the next adjacent chair, said side members being also positioned in respect to said front legs to permit the side members of a given chair to slide over the top end of a chair with which it is being nested.

2. A nestable chair comprising a pair of rear legs merging into a back, a pair of front legs, a U-shaped frame having diverging sides, said frame being open at the front, means for rigidly securing the rear part of the frame to said rear legs, means for rigidly securing said front legs to the front part of said frame so that said front legs will extend from the outer surface of the front of the frame inwardly to present an even outer ap-

pearance to the chair, said front legs having their upper ends substantially in the same plane as the lower edge of said frame, a hingedly mounted seat normally resting on said frame, and a filler block carried by said seat acting to fill the space between the seat and the front legs when the seat is resting on the frame, said block transmitting the strain from the seat to the legs, said seat extending forwardly of the frame sufficiently to reach the front portion of the front legs, said seat with the filler block being adapted to be swung upwardly and against said back when two or more chairs are to be nested in a horizontal direction, the side members of the respective nested chairs being positioned in respect to the front legs to permit the side members of one chair to slide, over the upper ends of the respective front legs of the next adjacent chair during the nesting operation.

3. A chair having a metallic seat frame, a seat member carried by said frame extending a short distance in front thereof, a pair of rear legs, a pair of front legs extending from the floor to said frame, but positioned immediately in front thereof, a bracket for each of said rear legs secured to said frame and extending vertically along part of said rear legs, screw means extending through said bracket and also through part of said frame and into said rear legs for rigidly securing the rear legs to said frame, a bracket for each of said front legs for securing the same to the front of said frame, each of said front brackets having a section overlapping part of one of the vertical faces of its associated front leg, a section sufficiently long to overlap the top of the said associated front leg and underlap part of said frame, and a web extending into the front leg, screw means extending through the last-mentioned brackets and into said front legs for rigidly holding the front legs in place and a filling block normally resting on each of said front legs, said filling block being carried by that part of said seat member extending beyond said frame.

4. A nestable chair, comprising a U-shaped frame open at the front, said frame having side members diverging from the rear toward the front and a cross bar at the rear, a pair of rear legs, a pair of front legs, said front legs extending upwardly to the lower surface of said frame and forwardly thereof, a bracket rigidly secured to said front legs at the upper end, said bracket being also rigidly secured to said side members at the front, means for rigidly securing the rear legs to said frame, a seat movably mounted on said frame and extending over said front legs, and a filler block for each of said front legs and extending from the front legs to the seat, said filler blocks being swingable to position away from said front legs and said seat and being movable away from said frame when two or more chairs are being nested.

5. A nestable chair including a seat structure, a substantially U-shaped frame normally supporting said seat structure, a pair of front legs secured to the front of said frame but extending only to the lower surface thereof, said front legs being positioned forwardly of said frame, a pair of rear legs secured to the rear of said frame, said U-shaped frame being open at the front and formed with a pair of diverging side members and a rear connecting transverse member, means for securing the upper end of each of said front legs to said frame at the lower margin of said side members, means for hingedly connecting said seat structure to said rear legs, said seat struc-

ture normally resting on said frame and extending forwardly sufficiently to be directly over said front legs, a filler member carried by the front part of said frame for each of said front legs, said filler members being positioned to fill the space between the top of said front legs and the bottom of said seat structure, said filler members and said seat structure being swingable to a position spaced from said front legs and said frame, said diverging side members and said frame being po-
5
10

sitioned relatively to said legs to permit the diverging side members of one chair to slide horizontally over the legs of an adjacent chair and within the diverging side members of said adjacent chair when said filler members have been 5
swung to a position away from said front legs, whereby identically constructed chairs may be nested from the front while remaining in a horizontal position.

LOUIS DELLERT. 10
